CLAIM

The ornamental design for a clasp set, as shown and described.

DESCRIPTION

FIG. 1 is a perspective view of a clasp set showing my new design. The broken lines showing the gemstone, gem settings and watch elements are for illustrative purposes only and form no part of the claimed design;

FIG. 2 is a top plan view. The broken lines showing the gemstone, gem settings and watch elements are for illustrative purposes only and form no part of the claimed design;

FIG. 3 is a side elevational view, the opposite side being a mirror image. The broken lines showing the gemstone, gem settings and watch elements are for illustrative purposes only and form no part of the claimed design; and,

FIG. 4 is a bottom plan view. The broken lines showing the gemstone, gem settings and watch elements are for illustrative purposes only and form no part of the claimed design.
